UNITED STATES PATENT OFFICE.

RALPH D. MOFFITT, OF LEXINGTON, NORTH CAROLINA.

COMPUTING PUMP.

1,303,708.

Specification of Letters Patent. Patented May 13, 1919.

Application filed September 6, 1916. Serial No. 118,698.

To all whom it may concern:

Be it known that I, RALPH D. MOFFITT, a citizen of the United States, residing at Lexington, in the county of Davidson and State of North Carolina, have invented new and useful Improvements in Computing-Pumps, of which the following is a specification.

This invention relates to improvements in computing pumps.

10 The object of the invention is to provide a pump of this character in which the amount of liquid delivered may be quickly and accurately determined without loss.

Another object is to provide a pump in 15 which the cost of the amount delivered may be correctly determined.

Other objects and advantages of the device will appear from the following description when taken in connection with the accompanying drawings.

In the drawings;

Figure 1 is a side elevation of a pump constructed in accordance with my invention.

Fig. 2 is a vertical sectional view of the 25 same;

Fig. 3 is an enlarged detailed view of one of the valves.

Referring specifically to the drawings the pump consists of a transparent container 30 designated by the numeral 1, said container having preferably upon its outer surface graduations 2 to determine the amount of liquid therein. Other graduations 3 used to determine the cost of the amount measured 35 are provided upon the container, these graduations having numerals corresponding to the price of the liquid to be dispensed.

The container is preferably formed of 40 glass and is mounted upon a suitable support 4, said support having connected thereto a supply pipe 5. This pipe is adapted to enter a suitable receptacle containing the liquid to be dispensed. A valve 6 controls the flow 45 of the liquid from this pipe into the container and this valve is automatic in action as will appear from the following description.

Located within the container is a pipe 8, 50 said pipe terminating within a short distance of the upper end of this container, and having its opposite end connected by means of a valve 9 with a pipe 10 leading into a pair of suction pumps 11. These suction pumps may be of any preferred construction 55 and while there is shown in the drawings two of these pumps it is of course understood

that one or more may be employed. As shown these pumps are connected together by means of their piston rod 12 and are operated by a crank 13. Any suitable connection between the crank 13 and the piston rods of the pumps may be employed. In addition to the valve 9 which is controlled by one of the pumps a similar valve 14 is provided for the other pump. The object of 60 these pumps is to withdraw air from the container 1 and create a vacuum or partial vacuum therein in order to lift the valve 6 and draw the liquid from the receptacle into the container through the pipe 5. The pumps 11 are preferably contained within a wooden casing 15 carried by the member 4 and pipe 5. A pipe 16 is in communication with the container 1, in order to deliver liquid therefrom, a suitable valve 17 controlling the flow of liquid from this pipe. A pipe 18 connects the pipe 8 and the valve 17, a suitable outlet port 19 being provided in the valve 17.

In the operation of the invention air is 65 expelled from the container 1 which creates a vacuum therein which causes the valve 6 to be lifted from its seat and liquid delivered into this container, this operation continuing until the liquid has reached a predetermined point. For instance if vinegar is being sold at the rate of 25¢ per gallon and it is desired to purchase 15¢ worth, the liquid is allowed to rise until it reaches the graduation opposite 15 under the column 70 25 at the top, when the valve 17 is opened. The opening of this valve destroys the vacuum through the medium of the branch pipe 18 and the outlet 19, immediately causing the valve 6 to seat and cutting off the 75 flow of liquid through the pipe 5. The opening of the valve 17 in addition to destroying the vacuum delivers the liquid contained within the container.

While the invention is shown as applied to 80 a pump for measuring vinegar it is of course apparent that it could be used for measuring liquids of any character, it being only necessary to make the graduations conform with the liquid to be sold.

105 All of the parts of the device that are in contact with the liquid are formed either of wood or of glass, so that there will be no danger of rust or corroding. All of the pipes 8, 16 and 18 are of glass, as is also the container, while the member 4 and the pipe 5 are formed preferably of wood.

110

Various changes in the form, operation and minor details of construction may be made without departing from the spirit or sacrificing any of the advantages of the invention.

What I claim is:—

A computing pump comprising a container formed of transparent material and having graduations thereon, a supply pipe 10 communicating with the bottom of the container, means for creating a vacuum within the container, an enlargement formed in the upper end of the supply pipe to provide a chamber of greater diameter than the bore

of the supply pipe, the shoulder formed at 15 the juncture of said bore and chamber defining a valve seat, a ball valve normally positioned upon said seat and lifted therefrom by the vacuum, a discharge valve communicating with the interior of said chamber, and a pipe extending across the top of the valve chamber above the ball valve and communicating with the discharge valve for destroying the vacuum and permitting the valve to seat.

In testimony whereof I affix my signature.

RALPH D. MOFFITT.
